(57) **CLAIM**

The ornamental design for “a cartridge for use with a vaporization device,” as shown and described.

DESCRIPTION

FIG. 1 is a perspective view of a cartridge for use with a vaporization device;

FIG. 2 is a top view of the cartridge of FIG. 1;

FIG. 3 is a bottom view of the cartridge of FIG. 1;

FIG. 4 is a left-side view of the cartridge of FIG. 1;

FIG. 5 is a right-side view of the cartridge of FIG. 1;

FIG. 6 is a front view of the cartridge of FIG. 1;

FIG. 7 is a rear view of the cartridge of FIG. 1; and,

FIG. 8 is a perspective view of the cartridge of FIG. 1, the cartridge being positioned within a receptacle of a body of the vaporization device.

In the drawings, the broken lines represent unclaimed subject matter and form no part of the claimed design. In FIG. 8, the broken lines showing the vaporization device are for environmental purposes only and form no part of the claimed design.

1 Claim, 5 Drawing Sheets
